Specification for Design.

Patented Nov. 4, 1919.

Application filed June 11, 1919. Serial No. 303,491. Term of patent 3½ years.

To all whom it may concern:

Be it known that I, MORRIS SCHLESINGER, a citizen of the United States, residing at New York, in the county and State of New York, have invented a new, original, and ornamental Design for Clusters for Floor and Table Lamps, of which the following is a specification, reference being had to the accompanying drawings, forming part thereof.

Figure 1 is a front elevation of a cluster for floor- and table-lamps, showing my new design; and Fig. 2 is a plan view thereof.

I claim:

The ornamental design for a cluster for floor- and table-lamps, as shown.

MORRIS SCHLESINGER.
